UNITED STATES PATENT OFFICE.

WILLIAM P. HAMMOND, OF CHARLESTOWN, MASSACHUSETTS, ASSIGNOR, BY MESNE ASSIGNMENTS, TO UNITED SHOE MACHINERY COMPANY, OF PATERSON, NEW JERSEY, A CORPORATION OF NEW JERSEY.

JOINT.

1,108,363.

Specification of Letters Patent. Patented Aug. 25, 1914.

Application filed September 17, 1912. Serial No. 720,789.

To all whom it may concern:

Be it known that I, WILLIAM P. HAMMOND, a citizen of the United States, and a resident of Charlestown, in the county of 5 Suffolk and State of Massachusetts, have invented an Improvement in Joints, of which the following description, in connection with the accompanying drawings, is a specification, like characters on the drawings representing like parts.

This invention relates to joints for couch beds, hammocks and other structures, and among other objects, provides a strong, effective joint which is simple to construct 15 and cheap to manufacture.

The character of the invention may be best understood by reference to the following description of an illustrative embodiment thereof shown in the accompanying 20 drawings, wherein:

Figure 1 is a plan view of a couch bed having frame members connected by an illustrative joint embodying the invention; Fig. 2 is a side elevation of the couch bed 25 shown in Fig. 1; Fig. 3 on an enlarged scale is a plan of portions of frame members disclosed in Fig. 1 showing the joint construction; Fig. 4 is an end elevation of Fig. 3; Fig. 5 is a section taken on line 5—5 of Fig. 30 3; and Fig. 6 is a perspective view of a detail to be referred to.

Referring to the drawing, the joint embodying the invention is shown for purposes of illustration in a couch bed comprising a 35 frame including side tubes 1 and end angle bars 3, between which is stretched a mattress 5. The frame and mattress thus formed may be supported by legs 7 suitably connected to the end angle bars 3 referred 40 to. The legs and side bars may be connected by diagonal braces 9.

Heretofore considerable difficulty has been experienced in providing a cheap, simple and effective joint for connecting the side 45 bars with the end bars. In some instances a leg of the angle bar has been laid on the rounded surface of the side bar, and riveted thereto. This was a very unsatisfactory construction since a loose pivotal connection 50 was formed which lacked rigidity and permitted relative rocking of the side tubes and end bars, causing skewing and other distortion of the frame.

One of the purposes of the invention is to provide a joint overcoming the above objections.

Referring more particularly to Figs. 3, 4 and 5, the illustrative joint embodying the invention comprises diametrically opposed terminal slots 11, 11 in the tube preferably 55 extending in the direction of the longitudinal axis of the tube. The angle bar 3 referred to comprises two flanges 3^a and 3^b. The former is set into said terminal slots and the latter faces the end of the tube and 60 partially closes the same. The slots and flange are preferably of substantially equal extents so that the edge 3^c of the flange may bear against the ends of the slots 11, 11. To secure the flange 3^a in the slots 11, 11 a 65 bolt, rivet, or other means 13 may be entered through said tube and flange 3^a transversely to the plane of the latter. By the construction described, the edge 3^c of the angle bar 70 flange 3^a bears against the ends of the tube 75 slots, which, being spaced a distance equal to the diameter of the tube, offers a two-point bearing for resisting relative rocking of the tube and bar in their plane. This 80 is further assisted by the rivet 13 which secures the angle bar flange in the slots and thereby holds the edge of the angle bar flange 3^a in bearing contact with the ends of 85 the slots. The flanges being fitted into slots of substantial lengths, prevents rocking of the angle bar relatively to the tube transversely to their plane. Preferably the face 90 of the vertical angle bar flange 3^b should abut against the end of the tube but this is not indispensable, since an effective rock-resisting bearing is had by the engagement of 95 the edge of the angle bar flange 3^a with the ends of the tube slots.

In some instances the angle bar edge 3^c 100 may terminate somewhat short of the ends of the tube slots, and in such case the rock-resisting bearing is had by the engagement of the angle bar vertical flange 3^b with the end of the tube. It is preferable, however, to have the bearing engagement between the 105 angle bar edge 3^c and the ends of the tube slots.

The joint described is extremely simple to construct, it being merely necessary to form the diametrically opposed slots in the ends of the tube; introduce a flange of the angle

bar into said slots; bore registering holes in said tube and angle bar flange; and then introduce the rivet through said holes.

While the bar shown herein as connected to the tube is an angle bar, it will be understood that the invention is not limited thereto, but that channel or other bars might be employed if desired.

It will be understood that the joint described is shown in a couch frame for illustrative purposes merely, since it is applicable to many other uses.

Having described one embodiment of the invention without limiting the same thereto, what I claim as new and desire to secure by Letters Patent is:

1. A rigid joint comprising a tube having at an end thereof a pair of opposite slots extending longitudinally of the tube, a right angle bar having one flange fitting in said slots and extending to the inner end thereof, and having its other flange engaging the end of the tube, and a bolt extending transversely through the end of the tube and

through said first mentioned flange, and securing the tube and bar in fixed relation.

2. A bed-frame or like structure consisting of two parallel side tubes, each of which has terminal slots at each end, extending transversely of the tube, and a pair of transverse, end, right angle bars each having a flange fitting the slots of the adjacent ends of said side bars and engaging the inner ends of said slots, said bars each having its other flange extending transversely of and abutting the said adjacent ends of said tubes, and a bolt extending transversely through each end of each tube and the inserted flange, the said bolts holding the tubes and angle bars in fixed, rigid relation.

In testimony whereof, I have signed my name to this specification, in the presence of two subscribing witnesses.

WILLIAM P. HAMMOND.
